(57) **CLAIM**

The ornamental design for a pliers hammer head, as shown and described.

DESCRIPTION

FIG. 1 is a perspective view of a pliers hammer head showing our new design;

FIG. 2 is a left side elevational view thereof;

FIG. 3 is a bottom side elevational view thereof;

FIG. 4 is a right side elevational view thereof; and,

FIG. 5 is a front end elevational view thereof.

The portions of the pliers illustrated in broken lines form no part of the claimed design.

1 Claim, 3 Drawing Sheets

FIG. 2

FIG. 3

FIG. 4

FIG. 5
